Primary Examiner — Amber R Stiles

Assistant Examiner — Molly K. Orzechowski

(74) *Attorney, Agent, or Firm* — Terence P. O'Brien

(57) **CLAIM**

The ornamental design for a footwear article, as shown and described.

DESCRIPTION

FIG. 1 is a front, side perspective of a footwear article;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The evenly-spaced broken lines depict portions of the footwear article that are environmental and form no part of the claimed design. The dot-dash broken lines depict the boundaries of the claimed design and form no part thereof.

1 Claim, 4 Drawing Sheets
